UNITED STATES PATENT OFFICE.

BERTRAM C. KENYON, OF MISHAWAKA, INDIANA, ASSIGNOR OF ONE-HALF TO DODGE MANUFACTURING COMPANY, OF MISHAWAKA, INDIANA, A CORPORATION OF INDIANA.

COMBINED PACKING-RING AND VALVE.

1,157,162.

Specification of Letters Patent.

Patented Oct. 19, 1915.

Application filed October 20, 1913. Serial No. 798,308.

To all whom it may concern:

Be it known that I, BERTRAM C. KENYON, citizen of the United States, residing at Mishawaka, in the county of St. Joseph and State of Indiana, have invented certain new and useful Improvements in Combined Packing-Rings and Valves, of which the following is a specification.

My invention relates to internal combustion engines and it specially appertains to such features as relate to packing rings which also serve the double purpose of valves to control the admission of fuel charges and provide outlets for the exhaust gases.

The purpose of my invention is to so construct a packing ring that it will serve to prevent leakage between the piston and the cylinder walls, also to combine therewith a self cleaning feature whereby carbon deposits on the edges of the cylinder ports are prevented and finally to dispense with the usual aggregation of puppet valves, etc., with their attendant noise and loss of efficiency after prolonged use. With this type of construction all the co-acting parts are kept in the best possible condition through there being a sliding relation between them, in consequence they are not subject to the serious pitting usually found in puppet-type valves. There is also provided a supplemental intake and exhaust which makes the action of the engine more flexible than with the ordinary single inlet and outlet openings.

With these ends in view I illustrate in the accompanying drawing such instances of adaptation as will disclose the broad features of my invention without limiting myself to the specific details shown.

Figure 1 is a vertical cross section of an engine embodying adaptations of my invention. Fig. 2 is a perspective view of a combined packing ring and valve. Fig. 3 is a plan view, in section through the main ports. Fig. 4 is a similar view through the supplementary ports. Fig. 5 shows a modified two-part packing ring. Fig. 6 is an enlarged section of the upper portion of the engine.

The engine is built on a base 1 which forms a space for the free movement of the crank and connecting rod. The base is open

at its upper face and on two opposite sides. Heads 2 and 3 are held in the side openings, 55 they have hubs 4 projecting inwardly and stuffing boxes 5. The hubs abut the crank 7, on each side, thus preventing endwise movement of the shaft 6. A pulley 8 is secured to one end of shaft 6 and a pinion 9 60 is fastened to the other end. A short shaft 10 rotates parallel with the main shaft 6, in head 3, at its inner end a bevel pinion 11 is fastened on its outer end a spur gear 12 is secured so as to mesh with the pinion 9 in 65 a 1:8 ratio. The gear 12 or shaft 10 may carry any suitable contacting device adapted to electrically ignite the fuel charges of the cylinder, with the usual spark retarding and advancing connections.

An annular recess 13 is formed on the upper face of the base 1, in which a flange 14 of the rotary sleeve 15 has bearing. This sleeve is surrounded by the cylinder 16 which may have an annular centering projection to register with the recess 13 directly above the flange 14 if desired. The cylinder 16 is secured to the base 1 in any suitable manner, such packing as may be required being placed between the base 1 and 75 the fastening flange 17. A bevel gear 18 is formed on the under edge of the sleeve 15, meshing with the bevel pinion 11 at an over-all ratio of 1 to 8 thus rotating the sleeve at the proper speed to harmonize 80 with the cycles of the sliding piston 19 operable within the sleeve, through its connecting rod 19 secured to pin 20 and the crank pin 21. The piston is provided with the usual type of packing rings and in its 85 extreme upper position it is some distance from the depending projection 22 of the cylinder head 23 so as not to cover the inlet ports of the sleeve packing ring 24.

The cylinder 16 has an inlet pipe 25 leading from the carburetor. Before the pipe reaches the cylinder at opening 26 a branch 27 is taken off, which forms a supplementary inlet 28 connecting with orifice 29. On the same plane as 29 a supplementary exhaust opening 30 is formed and a pipe 31 leads therefrom. Above the orifice 26 an annular exhaust chamber 32 is formed, connection thereto being made with exhaust pipe 33. This chamber has ports that 100 connect with the packing valve ring 24 and

openings formed therein and leading through the sleeve 15 into space 34 via small recesses 35 formed in the projection 22 of cylinder head 23.

5 A water cooling space 36 is formed around the cylinder and suitable connections are made therefrom to a similar cooling chamber formed in the head 23 so as to encircle the spark plug 37. The water is led in 10 through pipe 38 and out through pipe 39. Suitable provisions are made as at 40 for oiling the inside and outside faces of the sleeve 15. A binding post 41 serves for the attachment of the electrical connection for 15 firing the charge. A stationary packing ring 42 is placed around the projection 22 so as to "seal off" the extreme upper end of the sleeve 15 from the space 34.

Packing valve sleeve 24 is split diagonally, as at 43 and the edges of such split are left sharp so as to continuously scrape away any deposits of carbon that may form around the cylinder ports. The sleeve has a series of four upper openings 44 which 25 serve the exhaust function of the engine and another series of four lower openings 45 which are the inlet orifices leading from pipe 25 to the firing space 34. An opening 46 and a suitable pin is used to fasten the 30 ring to the sleeve 15 at one point opposite the slot 43 so that the ring 24 may freely expand and slide in close contact with the inner wall of the cylinder. Openings 44 are approximately radially opposite to each 35 other and the outlet ones 45 are similarly disposed from which it will be seen that the slot 43 has no effect on either the inlet or the exhaust. The sleeve 15 has a series of openings 47 formed therein so as to 40 "feather" the supplemental intake and exhaust and cause a gradual effect to be produced.

In order that the packing ring may be placed on the sleeve 15 without distortion a 45 solid ring 48 is slipped on and suitably pinned after the ring 24 has been placed in position. If desired the packing ring 24 may be made in two parts as shown in Fig. 5. Each part being separately held on the 50 sleeve 15 so as to break the continuity of slot 43. In this event duplicate fastening opening 46 would be formed in the upper half of the packing ring.

From the foregoing description it will be 55 seen that my device is simple to construct and efficient in operation, without having recourse to the usual complexity of parts. The supplemental supply of fuel is believed to be of value in securing a greater average 60 pressure throughout the piston stroke and also providing a more equable action, free from "wire drawing" than has heretofore been found in internal combustion engines.

If desired an ordinary packing ring may 65 be placed on the sleeve 15 below port ring

24 and any suitable oil grooves may be formed on the sleeve if deemed necessary.

What I claim is—

1. In internal combustion engines, a packing ring having a series of ports formed 70 therein, the said ring being discontinuous diagonally to the axis thereof.

2. In internal combustion engines, a packing member comprising a discontinuous ring having two series of openings formed 75 therein, the same being disposed at differential angular relations.

3. In internal combustion engines, a rotatable sleeve operable in a cylinder, a toothed flange at its inner end, a reduced 80 diameter at its outer end, a packing ring thereon, ports in the sleeve and ring in registry with each other, means adapted to cause the ring to rotate with the sleeve, a retaining member secured on the sleeve at its 85 outer end adapted to hold the packing ring in endwise position, a suitable cylinder, a head projecting into the sleeve, packing means on such head, and means for delivering lubricant adjacent the extreme outer 90 end of the sleeve.

4. In internal combustion engines, a rotatable sleeve, a cylinder surrounding the same, a piston slidably active therein, a packing ring carried by the sleeve, a diagonal slot, outlet and inlet openings formed 95 in said ring and means for holding the ring on the sleeve without destroying its elasticity.

5. In internal combustion engines, a cylinder, a piston operable therein, main inlet and outlet ports of maximum area, supplemental intake and outlet openings of reduced area, suitable valvular control for said ports and a series of adjacently placed 105 apertures adapted to gradually control the openings.

6. A suitable base, an annular recessed opening in the top thereof, annular openings on the opposing faces of said base, centrally alined heads adapted to seat within and against the opposing faces, a crank shaft supported by the heads, a cylinder concentric with the recess secured to the base, a rotatable cylinder lining resting in the said 110 recess, a piston within the same, and means for operatively and cōordinately connecting the sleeve and the piston to said shaft.

7. In internal combustion engines, a base, a crank shaft therein, a cylinder supported on 120 the base, a piston operable therein, connections therefrom to said shaft, main inlet and outlet openings of maximum area formed in said cylinder, supplementary intake and outgo apertures of minimum also formed 125 therein, and suitable valve mechanism adapted to control the relation of such openings to the movements of the piston.

8. In internal combustion engines, a cylinder, a removable head therefor, a projec- 130

tion leading therefrom into said cylinder, 5 portal recesses formed in the periphery of said projection, companion openings formed in the walls of the cylinder, and suitable valvular control therebetween.

9. In internal combustion engines, a suitable base, a cylinder attached thereto, a revoluble sleeve, a crank shaft having bearing in the base, connections from the piston to 10 the crank, other actuating connections from said shaft to said sleeve and means comprising a combined packing and valve ring carried by the sleeve having ports therethrough and a slot reaching from edge to edge where 15 by the intake, outgo of the cylinder and any deposits thereon are automatically controlled.

10. A suitable base, removable heads secured thereto in axial alinement with each 20 other, a cylinder supported opposite recessed opening of said base, a rotatable lining simultaneously operable in the base and cylinder, a piston within the lining, a crank shaft

in said heads, and means for actuating said shaft from the piston and said sleeve from 25 the shaft.

11. In internal combustion engines, a packing ring comprising two separate members operative adjacent each other, and differentially placed slots and ports in said 30 rings.

12. In internal combustion engines, a rotatable sleeve, a cylinder surrounding the same, a piston therein, one or more packing rings supported thereby, suitable openings 35 formed in said rings, and a removable retaining ring secured to the sleeve so as to prevent endwise displacement of the packing rings and also permitting of their being 40 assembled without distortion.

In testimony whereof I affix my signature in presence of two witnesses.
